US0D1013669S

(12) **United States Design Patent** (10) Patent No.: **US D1,013,669 S**
(45) Date of Patent: ** Feb. 6, 2024

(54) **MOBILE PHONE**

(71) Applicant: **Lenovo (Beijing) Limited**, Beijing (CN)

(72) Inventors: **Yunchao Zhang**, Beijing (CN); **Jun Liang**, Beijing (CN)

(73) Assignee: **Lenovo (Beijing) Limited**, Beijing (CN)

(**) Term: **15 Years**

(21) Appl. No.: **35/515,887**

(22) Filed: **Dec. 2, 2022**

(80) **Hague Agreement Data**

Int. Filing Date: **Dec. 2, 2022**

Int. Reg. No.: **DM/225705**

Int. Reg. Date: **Dec. 2, 2022**

Int. Reg. Pub. Date: **Dec. 30, 2022**
